[57] CLAIM

The ornamental design for a monitor support stand, as shown and described.

DESCRIPTION

FIG. 1 is a top, left, front isometric view of a first embodiment of a monitor support stand showing our new design; FIG. 2 is a left side elevational view thereof; the right side elevational view thereof being a mirror image of FIG. 2; FIG. 3 is a top plan view thereof; FIG. 4 is a bottom plan view thereof;

FIG. 5 is a front elevational view thereof; and, FIG. 6 is a rear elevational view thereof;

FIG. 7 is a top, left, front isometric view of a second embodiment of a monitor support stand showing our new design;

FIG. 8 is a left side elevational view thereof, the right side elevational view thereof being a mirror image of FIG. 8;

FIG. 9 is a top plan view thereof;

FIG. 10 is a bottom plan view thereof;

FIG. 11 is a front elevational view thereof; and, FIG. 12 is a rear elevational view thereof;

FIG. 13 is a top, front isometric view of a third embodiment of a monitor support stand showing our new design;

FIG. 14 is a left side elevational view thereof; the right side elevational view thereof being a mirror image of FIG. 14;

FIG. 15 is a top plan view thereof;

FIG. 16 is a bottom plan view thereof;

FIG. 17 is a front elevational view thereof; and,

FIG. 18 is a rear elevational view thereof.
